DECORATIVE PANEL FOR FURNITURE DOOR, DRAWER FRONT, HEADBOARD OR THE LIKE

Aaron Donner, Weston, Conn., assignor to
The Lane Company

Filed July 10, 1974, Ser. No. 487,380

Term of patent 14 years

Int. Cl. D6—06

U.S. Cl. D6—192

FIG. 1 is a front perspective view of a decorative panel for a furniture door, drawer front, headboard or the like showing my new design;

FIG. 2 is a right side elevational view;

FIG. 3 is a front elevational view;

FIG. 4 is a top plan view;

FIG. 5 is a front perspective view of a second embodiment of a decorative panel showing my new design.

FIG. 6 is a front elevational view of a third embodiment of a decorative panel showing my new design.

The rear of each panel is plain and unornamented.

I claim:

The ornamental design for a decorative panel for furniture door, drawer front, headboard or the like, as shown and described.
